[57] CLAIM

The ornamental design for an enclosure for a portable handheld transmitter, as described.

DESCRIPTION

FIG. 1 is a front elevational view of an enclosure for a handheld transmitter according to my design, the reverse side being flat and without ornamentations; FIG. 2 is a side elevational view of the enclosure of FIG. 1, the reverse side being a mirror image thereof; and

FIG. 3 is a top elevational view of the enclosure of FIG. 1, the reverse side being a mirror image thereof.

FIG. 1

FIG. 2

FIG. 3

UNITED STATES PATENT AND TRADEMARK OFFICE
CERTIFICATE OF CORRECTION

PATENT NO. : Des. 273,786

DATED : May 8, 1984

INVENTOR(S) : John R. Owerko

It is certified that error appears in the above-identified patent and that said Letters Patent are hereby corrected as shown below:

On the title page,

Change inventor's name to read
